UNITED STATES PATENT OFFICE.

GEORGE F. PEMBERTON, OF LINCOLN, CALIFORNIA, ASSIGNOR TO GLADDING, McBEAN & COMPANY, OF SAN FRANCISCO, CALIFORNIA, A CORPORATION OF CALIFORNIA.

BRICK-CUTTING MACHINE.

1,302,964.

Specification of Letters Patent.

Patented May 6, 1919.

Application filed March 21, 1917. Serial No. 156,281.

To all whom it may concern:

Be it known that I, GEORGE F. PEMBERTON, a citizen of the United States, residing at Lincoln, in the county of Placer and State 5 of California, have invented new and useful Improvements in Brick-Cutting Machines, of which the following is a specification.

This invention relates to machines for cutting freshly made blank bricks or plastic blocks into irregular shapes, whereby to 10 form bricks for use in arches and elsewhere where tapering, trapezoidal or other shapes are required.

The object of the invention is to provide 15 a simple and efficient device of this character which will reduce the labor involved in cutting the bricks and which will also be adjustable to provide for cutting a variety of shapes and sizes in one machine.

20 In carrying out this object, I employ a stationary support to receive the freshly made blank bricks and a plunger carrying an open rectangular frame across which wires or other cutting devices are stretched 25 and positioned according to the shape, form and number of bricks desired, and means for depressing the plunger whereby to press the rectangular frame against the support to cause the wires to pass through the blank 30 brick and cut the same into one or more bricks of the required size and shape.

One form which my invention may assume 35 is exemplified in the following description and illustrated in the accompanying drawings, in which—

Figure 1 shows a side elevation of a machine embodying my invention.

Fig. 2 shows a plan view in section taken on the line 2—2 of Fig. 1.

40 Fig. 3 shows the manner of securing the ends of the cutting wires to the frame.

In the drawings, the machine is shown 45 as comprising a support 10, upon which vertical frame bars 11, with top and bottom plates 12 and 13, respectively, are secured. Reciprocally mounted upon the support is a plunger comprising vertical rods 14 working in bearings 15 on the top and bottom plates 12 and 13, said rods being tied together at 50 their upper ends by a cross head 16. Positioned upon the rods 14, between the top and bottom plates, is a rectangular open frame 17, the side bars of which are slotted at suitable intervals, as shown at 18, to receive 55 a bolt or pin 19 for adjustably securing

a plate 20 thereon. Below each slot 18 the side bars are recessed, as shown at 21, to receive a hook 22 held adjustably in place on the lower end of the plate 20 by means of a thumb screw 23. To the opposite hooks 22 wires 24 are connected and stretched to the desired degree of tautness and adjusted relatively by positioning the plates 20 until the required outlines of the bricks to be produced are obtained.

60 A bar 25 is pivoted to the top plate 12 and a lever 26 is fulcrumed thereon, said lever being connected to the cross head 16 and carrying a weight 27 at its outer end.

65 In operation, a pad 28, of suitable material, is placed upon the bottom plate 13 and the blank brick to be operated upon is set thereon. The plunger is normally elevated on account of the weighted lever, and by movement of the lever the rectangular 70 open frame is pressed downwardly upon the pad 28, so that the wires thereon pass through the blank and cut the same into one or more bricks of the size and shape desired. The wires are adjustable to produce any of 75 the usual forms required for arch bricks or other shapes. The machine may obviously comprise any number of wires, in any arrangement desired, whereby to produce a plurality of bricks of the same or different 80 shapes and sizes at one operation and also 85 may be operated by power, if desired.

Various changes in the construction and arrangement of the several parts herein 90 shown and described may be employed without departing from the spirit of my invention as disclosed in the appended claims.

Having thus described my invention, what I claim and desire to secure by Letters Patent is—

1. A machine for cutting freshly made bricks or plastic blanks into different shapes, comprising a main stationary frame, a stationary support for the blank within said frame, a rectangular-shaped cutting frame vertically movable in the main frame, manually operated means for imparting movement thereto, longitudinally disposed slots 100 formed in the sides and ends of the cutting frame, blocks slidably and adjustably mounted in each slot, means on each block for securing the same when adjusted, wire securing and tightening means carried by the blocks and recesses formed in the lower 105 110

- edge of the side and end sections of the cutting frame, permitting the wires to assume a plane parallel with the lower face of the cutting frame.
- 5 2. A machine for cutting freshly made bricks or plastic blanks into different shapes, comprising a main stationary frame, a stationary support for the blank within said frame, a rectangular-shaped cutting frame vertically movable in the main frame, guiding members secured to said frame and reciprocal in the main frame, means for imparting an up and down movement to the cutting frame, the sides and ends of said cutting frame being angle-shaped in cross section, longitudinally disposed slots formed in the sides and ends of the angle-shaped cutting frame, blocks engaging the inner and exterior sides of the side and end sections 10 of the cutting frame, said blocks being slidably and adjustably mounted in the slots,
- 15
- 20

means on each block for securing the same when adjusted, said blocks being arranged in pairs to support cutting wires, hooks formed on one of each pair of blocks for the reception of a cutting wire, tightening means on the opposite block of each pair for tightening and securing the wires and recesses formed on the lower edge of the angle-shaped side and end sections of the cutting frame for the reception of the wires and to permit the wires to assume a plane parallel with the lower edges of said side and end sections.

In testimony whereof I have hereunto set my hand in the presence of two subscribing witnesses.

GEORGE F. PEMBERTON.
